UNITED STATES PATENT OFFICE.

HENRY A. WISE WOOD, OF NEW YORK, N. Y., AND CONRAD NORDFORS, OF JERSEY CITY HEIGHTS, NEW JERSEY, ASSIGNEES TO WOOD NEWSPAPER MACHINERY CORPORATION, OF NEW YORK, N. Y., A CORPORATION OF VIRGINIA.

FOLDING AND COLLECTING MECHANISM.

1,321,581.

Specification of Letters Patent. Patented Nov. 11, 1919.

Application filed February 2, 1915, Serial No. 5,642. Renewed April 23, 1919. Serial No. 292,240.

To all whom it may concern:

Be it known that we, HENRY A. WISE WOOD and CONRAD NORDFORS, citizens of the United States, said Wood residing at New York, in the county of New York and State of New York, said NORDFORS residing at Jersey City Heights, county of Hudson, and State of New Jersey, have invented a new and useful Folding and Collecting Mechanism, of which the following is a specification.

This invention relates to a folding delivery in which one of the cylinders thereof is adapted to cut, fold and deliver a sheet on each revolution from a continuous web, or to collect on alternate revolutions, so as to deliver the successive papers folded in pairs.

The principal objects of the invention are to provide an exceedingly simple arrangement for effecting the change, and more specifically, an arrangement in which the change is made simply by fixing a gear against rotating and rendering another gear inoperative, or vice versa; to provide for operating the piercing points of the cutting and collecting cylinder from the rotary carrier or delivery cylinder when it is desired to collect, and to operate said pins from a stationary member when it is desired to operate without collecting; also to provide improvements in details of the mechanism for operating the pins and improved means whereby one of the sets of grippers on the delivery cylinder can be thrown out of operation conveniently to permit their delivering only once for each revolution of that cylinder.

The invention also involves improvements in details of construction and combinations of parts as will appear.

Reference is to be had to the accompanying drawings in which,

Figure 1 is an elevation of a preferred embodiment of the invention showing it from the side of the press;

Fig. 2 is an end elevation of the press frame showing the same device;

Fig. 3 is an enlarged view of the gripping device on the delivery cylinder in position to rotate to grip and fold a sheet;

Fig. 4 is a similar view showing these parts thrown into inoperative position;

Fig. 5 is a diagrammatic view of the collecting cylinder and part of the delivery

cylinder showing the position of the parts 55 when a sheet is just being cut off and the advance end of the web pierced by the pins;

Fig. 6 is a similar view showing the collecting cylinder advanced a half a revolution and the delivery cylinder a quarter of a 60 revolution, the parts being in condition for collecting;

Fig. 7 is a similar view showing the collecting cylinder rotated a complete revolution from the position shown in Fig. 5; and 65

Fig. 8 is a similar view showing the position of the parts at the next half revolution of the collecting cylinder with the two sheets just ready to be folded and taken away by the delivery cylinder. 70

The mechanism is shown as mounted on the frame A of a web printing machine. In the form illustrated, the mechanism consists mainly of a folding, cutting and collecting cylinder B, and a rotary carrier or 75 delivery cylinder C. These cylinders are mounted on shafts 7 and 8, respectively, carried in bearings on the frame. The main driving gear train, not shown, imparts power to a gear 9 on the shaft 8 which meshes with a gear 10 on the shaft 7. These two gears bear the same relation to each other, as to diameter, as the two cylinders, and consequently drive the two cylinders at the same circumferential speed. 80

In the form shown, the cylinder B is half the diameter of the cylinder C and consequently rotates twice to each rotation of the latter. 85

The cylinder B is provided with the usual cutting knife 11, folding or tucking blade 12, and pin points 13. These pin points are arranged in a row and adapted to reciprocate, and each one is operated by a gear segment 14. These segments are mounted 90 on a rod or shaft 15 which is adapted to oscillate, and is provided with a crank arm 16 provided with a pin 17. This pin operates in a hole in a circular ring 18. This ring is loosely mounted on the eccentric hub of a gear 19. This gear runs loose on the shaft 7. 95

On the frame A is a bolt 21 which is adapted to be moved in so as to enter a depression formed in a boss 20 on the face of the gear 19. When this is done, as shown in Fig. 2, the gear 19 will be held in stationary position. This is the condition required 100 when the cylinder B is not collecting. 105

On the shaft 8 is a gear 22 of the same diameter as the gear 19. This is designed to operate the gear 19 when the bolt 21 is withdrawn, and when it is desired to operate the device to collect. For this purpose this gear 22 is shown as slidably splined to the shaft 8 and to be capable of moving from the full line position in Fig. 2, in which it is inoperative, to the dotted line position in which it meshes with the gear 19.

Referring now to the rotary carrier or delivery cylinder C, it will be seen that it is provided with two sets of folding grippers 23 and 24. Each of the grippers consists of a roller mounted to oscillate on its own end studs. The studs of the grippers 23 are mounted in bearings or boxes 25 forming part of the cylinder and of course moving therewith. On one end of this gripper 20 is fastened a crank lever 26 which has a projecting pin 27 operating in a groove of a cam 28. This cam is fixed on the frame A. To prevent the operation of the crank levers 26 by the cam 28 operating one pair of grippers 25 when it is desired to collect, a set screw 29 is provided in each crank lever 26 for holding it on the stud of the gripper. One of these is simply loosened when it is desired to silence a pair of grippers so as to permit this crank lever to swing loosely on the gripper stud. This is done when the grippers of this set are held in inoperative position by means of the spring pin 33. The other end of the gripper or the stud with which it is provided at that end, has a gear segment 30 meshing with a similar gear segment 31 on the end of the other gripper 24. The gear segment 30 is provided with a projection or boss 32 carrying a spring pin 33. On the face of one of the bearing boxes 25 is a hole 34 into which the pin 33 is adapted to be projected, in order to render these grippers inoperative. One pair of grippers is ordinarily silenced when collecting.

The grippers 24 operate in bearings 35 of a pair of bell-cranks 36. These bell-cranks are pivoted on studs 37 attached to the cylinder. They are provided with springs 38 to give the necessary flexible grip between the grippers. Adjustable stop screws 39 are mounted in puppets 40 fastened to the cylinder C to regulate the necessary openings between each pair of grippers.

It is to be understood that as we have shown the cylinder C of twice the diameter of the cylinder B, the latter cylinder will rotate twice for each rotation of the former, and consequently there are two sets of grippers 60 on the cylinder C and only one folding blade on the cylinder B. When it is desired to deliver every sheet, the gear 19 is fixed in stationary position by means of the bolt 21 and the gear 22 is moved over to the full line position of Fig. 2 where it will be in-

operative. Furthermore, both sets of grippers of the cylinder C are left in operative condition. In this case the operation of the cam ring 18 causes the pin points 13 to be projected once during each revolution of the cylinder B and that at a time when the cylinder C is in the position shown in Fig. 1. Thus the pins will have perforated the end of the web at this point at the time at which the sheet in advance has just been severed. The pins are projected at this point and they are fully withdrawn when the cylinder B has performed the half revolution from the position shown in Fig. 1. In the latter position, the end of the web 75 has advanced half way around the cylinder B and the tucking blade 12 is in position to tuck the web in between the grippers 23 and 24. The two cylinders are in the relative position then indicated in Fig. 6, but 80 the pin points at the top are not projected, as shown in that figure, but are withdrawn while the grippers 23 and 24 are swung outwardly ready to grip the sheet and fold it over the folding blade. On the next half 85 revolution of the cutting cylinder B, the parts thereof are again brought back to the position shown in Fig. 1. The grippers have carried the folded sheet away from the cutting cylinder, the tail end of the sheet 90 is just being severed by the cutting knife 11, and the leading end of the web has been punctured by the pin points, ready to repeat its operation.

In order to cause no unnecessary strain 100 on the folded web while carried from the folding point to the point at which the grippers begin to grip, the cam 28 is so constructed as to allow the grippers to remain in a relative stationary position from 105 the point at which they grip the sheet from the cutting cylinder, to the point shown at the left in Fig. 1. From this point to the bottom of the delivery cylinder the grippers move outwardly, that is, they have an ejecting motion so that they can eject the bite 110 of the sheet and drop it on the conveyer belt 41. Thus the grippers have a slight pulling-in motion, while the web is being tucked in the bite between them, but that 115 immediately ceases and from that point until the web is about to be ejected, they remain stationary. After this they commence to eject the folded paper and drop it on the belts. The rest of the rotation is 120 an idle one, so far as any action by these grippers on the sheet is concerned, but during that rotation they are brought slightly inwardly so as to get them ready for pulling in the sheet when they again reach the 125 tucking-in position at the top.

When it is desired to collect two papers on the cylinder B and then discharge them together, the pin bolt 21 is withdrawn from the gear 19, leaving it free to revolve, and 130

the gear 22 is moved along its shaft so as to mesh with the gear 19 and positively drive it at the same speed as that of the shaft 8. The set screw 29 connected with one of the 5 grippers is loosened to render that gripper inoperative, and the spring pin 33 connected with the same pair of grippers is moved over into the hole 34. This effectively renders the grippers on one side of 10 the delivery cylinder inoperative.

As the two gears 19 and 22 have the same diameter, and as the cylinder B has half the diameter of the cylinder C, the gear 19 will rotate at half the speed, in revolutions 15 per minute, of the cylinder B on the same shaft. Consequently, the eccentric ring 18 will operate the piercing pins 13 only once for each two revolutions of the cutting cylinder B. Furthermore, the delivery 20 cylinder will operate to deliver a sheet, or plurality of sheets, only once for each revolution, instead of twice, as in the case above described. Therefore, the operation will take place as indicated in the diagrammatic views, Figs. 5 to 8.

In the position shown in Fig. 5, and also shown in Fig. 1, a sheet has just been severed and the leading end of the web pierced by the pins. Now upon the next 30 half revolution of the cylinder B the pins are forced farther through the leading end of the web and it is taken half way around the cylinder. At this time the folding blade 12 is in folding position, but as the pair 35 of grippers on the other cylinder which now come into registration with it have been rendered inoperative, no folding action takes place. (See Fig. 6.)

On the next half revolution the sheet is 40 drawn the rest of the way around the cylinder B and the pins project through the leading end of the web again, while the knife severs the web at this point. This is shown in Fig. 7.

The cylinder B then rotates another half 45 revolution, which causes the pins at the top to withdraw from the double thickness of paper which they have previously pierced. At the same time the opposite 50 pair of grippers on cylinder C, which is in operative condition, comes into registration with the folding blade and receives the double fold therefrom. During the next half revolution the folded product is with- 55 drawn from the cutting cylinder and the parts reach the position shown in Fig. 1 and are ready to start the collection of two more sheets.

It will be understood that although we 60 have illustrated and described a machine constructed for collecting only two sheets, yet the same principles can be applied when a larger number of sheets are to be collected, and other changes can be made in details of 65 construction without departing from the

scope of the invention as expressed in the claims. Therefore we do not wish to be limited in these respects, but what we do claim is:—

1. In a cutting and folding mechanism, 70 the combination with a cutting and collecting cylinder having a folding blade thereon, of a rotary carrier having means for receiving the folded product therefrom and delivering the same, the cutting cylinder being 75 of half the diameter of the carrier and being rotatable twice to each revolution of the carrier, means on the shaft of the cutting cylinder, having connections for controlling the collecting operation thereon, and means 80 whereby said controlling means can be held in stationary position when it is not desired to collect and can be rotated at the same number of revolutions per minute as the carrier when it is desired to collect. 85

2. In a folding and delivering mechanism, the combination with a cutting, folding and collecting cylinder having a folding blade thereon, of a rotary delivering cylinder co-operating therewith for receiving folded 90 products therefrom and delivering them, a series of pin points carried by the first named cylinder, an eccentric for operating said pin points to move them out of and into operative position, means whereby when 95 said eccentric is held in stationary position the pin points will be projected once during each revolution of the first named cylinder, and means whereby the eccentric can be rotated once for each plurality of revolutions of the first named cylinder and the pin points projected once for a plurality of revolutions to permit collecting sheets on the first named cylinder. 100

3. In a machine of the class described, the 105 combination of a cylinder having pin points mounted thereon, a crank connected with said pin points for operating them, a gear loosely mounted on the shaft of said cylinder and having an eccentric for operating 110 said crank while the cylinder rotates at a different speed from the gear, means for holding the gear in stationary position, and means whereby the gear can be turned once for a plurality of revolutions of the cylinder. 115

4. In a machine of the class described, the combination of a cylinder having a cutting knife and a folding blade thereon, pin points reciprocably mounted on said cylinder, 120 means for operating said pin points, comprising a shaft with which the pin points are connected, a crank on the shaft, a gear loosely mounted on the shaft of said cylinder and having an eccentric, means for operating said crank by said eccentric to cause the pin shaft to turn once during each revolution of the cylinder, provided the gear is held in stationary position, means for holding the gear in stationary position, and 125 130

means whereby said gear can be turned once for a plurality of revolutions of the cylinder.

5. In a machine of the class described, the combination of a cylinder having a cutting knife and a folding blade located diametrically opposite each other thereon, pin points reciprocably mounted on said cylinder, means for operating said pin points comprising a shaft with which the pin points are connected, a crank on the shaft, a gear loosely mounted on the shaft of said cylinder and having an eccentric, means for operating said crank by said eccentric to cause the pin shaft to turn once during each revolution of the cylinder, provided the gear is held in stationary position, a carrier shaft rotatable at half the speed of the cylinder shaft, and a gear of the same size as the first named gear mounted on the carrier shaft and adapted to mesh with the first named gear, whereby said eccentric can be turned once for each two revolutions of the cylinder.

25 6. In a machine of the class described, the combination of a cylinder having a cutting knife and a folding blade thereon, pin points reciprocably mounted on said cylinder, means for operating said pin points, a gear loosely mounted on the shaft of said cylinder and having means for operating said pin shaft to turn once during each revolution of the cylinder, provided the gear is held in stationary position, a carrier shaft 30 rotatable at half the speed of the cylinder shaft, and a gear of the same size as the first named gear mounted on the carrier shaft and adapted to mesh with the first named gear, whereby said gear can be turned once 35 for each two revolutions of the cylinder.

45 7. In a machine of the class described, the combination of a cylinder having a cutting knife and a folding blade thereon, pin points reciprocably mounted on said cylinder, means for operating said pin points, a gear loosely mounted on the shaft of said cylinder and having means for operating said pin shaft to turn once during each revolution of the cylinder, provided the gear 50 is held in stationary position, a carrier shaft rotatable at half the speed of the cylinder shaft, a gear of the same size as the first named gear mounted on the carrier shaft and adapted to mesh with the first named gear, whereby said gear can be turned once 55 for each two revolutions of the cylinder, a carrier on said carrier shaft, two sets of grippers on the carrier, and means for silencing one set of grippers.

60 8. In a folding delivery, the combination with a cutting, folding and collecting cylinder, of a carrier for the sheets running in contact therewith at the same circumferential speed but of twice the diameter, means 65 whereby the cutting cylinder can be ren-

dered operative to deliver at each rotation or at each alternate one, so as to collect two sheets in the latter case, before delivering, two pairs of grippers mounted on said carrier opposite each other, a stationary cam 70 for operating said grippers to grip a sheet or sheets and to carry them away from the folding cylinder, each of said grippers comprising a shaft having a crank lever thereon for engaging said cam, and means whereby 75 the crank lever on one of said shafts can be released without removing it so as to be free to turn without turning the shaft, whereby one of the pairs of grippers will be rendered inoperative.

80 9. In a folding delivery, the combination with a cutting, folding and collecting cylinder, of a carrier for the sheets running in contact therewith at the same circumferential speed but of twice the diameter, means 85 on the cutting cylinder for rendering it operative to deliver at each revolution or at each alternate one, so as to collect two sheets in the latter case, before delivering, two pairs of grippers mounted on said carrier opposite each other, a stationary cam for operating said grippers to grip a sheet or sheets and to carry them away from the folding cylinder, each of said grippers comprising a shaft having a crank lever thereon for engaging said cam, means whereby the crank lever on one of said shafts can be released so as to be free to turn without turning the shaft, whereby one of said pairs of grippers will be rendered inoperative, and each pair of grippers also comprising a 90 spring pin, and means on the carrier for holding said spring pin in a position in which the grippers are withdrawn within the circumference of said carrier while rendered inoperative.

95 10. In a folding delivery, the combination with a folding cylinder, of a carrier for the sheets, two pairs of grippers mounted on said carrier opposite each other, a stationary cam for operating said grippers to grip a sheet or sheets and to carry them away from the folding cylinder, each of said grippers comprising a shaft having a crank lever thereon for engaging said cam, means whereby the crank lever on one of said shafts can be released so as to be free to turn without turning the shaft, whereby one of said pairs of grippers will be rendered inoperative, and each pair of grippers also 100 comprising a second gripper and gripper shaft, gear segments on the shafts meshing with each other, a spring pin connected with one of said segments, and means on the carrier for holding said spring pin in a position in which the grippers are withdrawn within the circumference of said carrier while rendered inoperative.

11. In a folding delivery, the combination with a folding cylinder, of a carrier for 105

the sheets having grippers, a stationary cam for operating said grippers to grip a sheet and carry the same away from the folding cylinder, said gripper having a crank lever for engaging said cam, means whereby the crank lever can be released so as to be free to turn without operating the gripper, the gripper also comprising a second gripper and a shaft, gear segments on the shaft meshing with each other, a spring-pin connected with one of said segments, and means on the carrier for holding said spring-pin in a position in which the grippers are withdrawn within the circumference of said carrier when rendered inoperative.

10 5

meshing with each other, a spring-pin connected with one of said segments, and means on the carrier for holding said spring-pin in a position in which the grippers are withdrawn within the circumference of the carrier when rendered inoperative.

15 10

12. In a folding delivery, the combination with a folding cylinder, of a carrier for the sheets, two pairs of grippers mounted on

said carrier opposite each other, each pair of grippers comprising two gripper shafts, 20 gear segments on the shafts meshing with each other, a spring pin connected with one of said segments, and means on the carrier for holding said spring pin in a position in which the grippers are withdrawn within 25 the circumference of said carrier and rendered inoperative.

In testimony whereof we have hereunto set our hands in the presence of two subscribing witnesses.
